Inventor

Stanislaus Thomas Drozdynski

By his Attorney Oscar Glier

UNITED STATES PATENT OFFICE.

STANISLAUS THOMAS DROZDZYNISKI, OF TOLEDO, OHIO.

FLEXIBLE-LADDER SUPPORT.

1,395,563.

Specification of Letters Patent.

Patented Nov. 1, 1921.

Application filed September 10, 1918. Serial No. 253,358.

To all whom it may concern:

Be it known that I, STANISLAUS THOMAS DROZDZYNISKI, a citizen of the United States, residing at Toledo, county of Lucas, and 5 State of Ohio, have invented certain new and useful Improvements in Flexible-Ladder Supports, of which the following is a specification.

This invention relates to improvements in 10 supports for flexible ladders and particularly to types adapted to be used as fire escapes.

The principal object of the invention is to provide a device upon which a flexible wire 15 ladder may be rolled or unrolled, the device being detachably engaged on the inner side of a window or like opening in the walls of a building, in such manner that the ladder may extend downwardly to the ground.

20 A still further object is to provide means which may be quickly and securely attached to the window frame without special arrangement for its support.

These and other like objects are attained 25 by the novel construction and combination of parts hereinafter described and shown in the accompanying drawing, forming a material part of this disclosure, and in which:—

Figure 1 is a front elevational view showing 30 a fragmentary portion of a building and indicating the application of the invention.

Fig. 2 is a vertical sectional view taken substantially on line 2—2 of Fig. 1.

Fig. 3 is a perspective view showing the 35 device in a partially unrolled condition, and

Fig. 4 is a fragmentary sectional view taken through one of the attaching means.

In the drawings, the numeral 10 represents the wall of a building containing a window 40 frame 11 in which are slidably engaged the sashes 12, both shown to be in a raised position so as to leave a clear opening 14 through the wall.

The ladder as shown consists of a pair of 45 parallel spaced flexible supports or side elements 15 having engaged between them at uniformly spaced intervals rungs 16, the ladder normally being coiled upon a drum 18, provided with raised annular flanges 19 at 50 its ends and passing through the drum is a spindle 20, provided with an extending operating crank handle 21 by which the drum may be rotated.

Secured on the extending ends of the spindle 55 20 are a pair of flat extending bars 23, these bars being adapted to extend outwardly

through the opening 14, and having formed with their lower ends, sharply pointed spur like projections 24, adapted to engage with the exterior of the wall of the building, preventing the bars from lateral movement and also materially assisting in supporting the device. 60

Journaled in the extreme lower ends of the bars 23 is a spindle 25, having upon it a 65 roller 26 over which the ladder 15 operates as it is rolled or unrolled from the drum 18.

Integrally formed with the upper end of the bars 23 are projections 28 extending angularly upward toward the front and pivoted in their outer end, on the pins 29, are double dogs 30, their points being operatively engaged with the teeth of escapement wheels 31, rigidly engaged upon the spindle 20, closely adjacent to the flanges 19, so that 70 as the ladder is unrolled and the drum caused to rotate, the double dogs are operated to engage each with one of its teeth, as the case may be, the teeth of its escapement wheel, so that each tooth acts as an impediment 75 tending to reduce the speed of the rotary movement of the drum in one direction so as to avoid too rapid descent of the ladder and consequent danger. 80

In order to attach the device in the window opening, there are secured to the outer side of the bars 23 opposed pairs of extending tubular supports 33, containing resilient compression springs 34, one end of which abuts against the outer side of the bars 23, 90 and the other against a disk like collar 35, fixed midway in the length of a rod 36 and slidably mounted in the end of the cylindrical projection 33, the rod also passing through the bars 23 so as to be held relatively 95 rigid.

Secured to the outer ends of the rods 33 are heads 37, the same being used as knobs in pressing the rods 36 inwardly, against the springs 34, it being understood that when the 100 knobs are pressed inwardly, the entire apparatus may be moved through the opening 14 in the wall, whereupon the springs will press the knobs and rods outwardly to such a length as to cause them to engage with the 105 inner surface of the wall or the window frame in an obvious manner, thus holding the device against movement as is clearly indicated in Fig. 2. Pendulum weights 38 are secured to the lower ends of rods 39, the upper ends of which are branched to form substantially triangular shaped elements 40 at 110

tached to the upper edges of the pallets 30 at both sides of the pivot points 29 of the same.

Having thus described my invention and 5 indicated in the manner of its construction and use, what I claim as new and desire to secure by Letters Patent, is—

In a flexible ladder support, the combination 10 of a spindle provided with an operating handle, a pair of flat bars supporting said spindle, spurs at the lower ends of the bars for engaging the outer wall of a building, a spindle journaled in the extreme lower ends of said bars, said spindles adapted to

guide and receive the flexible ladder, rods 15 laterally secured in said bars, tubular supports for said rods on the outer sides of said bars, resilient springs in said supports abutting with one end against the outer sides of said bars and with the other against collars 20 on said rods within said tubular supports, and operating heads on the outer ends of said rods for permitting an attachment of the ladder support in a window opening, substantially as described. 25

In testimony whereof I have affixed my signature.

STANISLAUS THOMAS DROZDZYNKI:
